UNITED STATES PATENT OFFICE.

RALPH R. BEAL, OF PALO ALTO, CALIFORNIA, ASSIGNOR TO AUGUSTUS TAYLOR, OF SAN FRANCISCO, CALIFORNIA.

RADIO OSCILLATION GENERATOR.

1,410,730.

Specification of Letters Patent. Patented Mar. 28, 1922.

Application filed January 5, 1920. Serial No. 349,473.

To all whom it may concern:

Be it known that I, RALPH R. BEAL, a citizen of the United States, and a resident of Palo Alto, county of Santa Clara, and State 5 of California, have invented a certain new and useful Radio Oscillation Generator, of which the following is a specification.

The invention relates to generators of electrical oscillations for the purpose of radio 10 communication and more particularly to a generator in which an arc is produced in a transverse magnetic field and in a hydrogen atmosphere.

An object of the invention is to provide 15 a radio oscillation generator of the arc type having an efficient magnetic circuit and a readily accessible arc chamber.

Another object of the invention is to provide 20 a magnetic circuit in which the leakage flux is reduced to a minimum. This is of decided advantage on shipboard, where the magnetic leakage would produce a deleterious effect upon the ship's compass.

A further object of the invention is to provide 25 an efficient and compact generator.

The invention possesses other advantageous features, some of which, with the foregoing, will be set forth at length in the following description, where I shall outline in full that 30 form of the invention which I have selected for illustration in the drawings accompanying and forming part of the present specification. In said drawings I have shown one specific form of oscillation generator of my invention, but it is to be understood that I do not limit myself to such form, since the invention, as expressed in the claims, may be embodied in a plurality of forms.

Referring to said drawings: 40 Figure 1 is a vertical section of the generator in closed position taken on the line 1—1, Figure 2.

Figure 2 is a top view of the generator with the upper section removed.

In order to obtain an efficient magnetic circuit, it is necessary to reduce the leakage flux to a minimum. This is accomplished in the present structure by placing the magnetizing coils on both sides of the chamber 45 in which the arc burns and preferably above and below the arc chamber. It is also necessary to provide a return magnetic circuit having a minimum reluctance, to keep the leakage at a minimum, and this is accomplished

by reducing the length of the return magnetic circuit to as small a value as possible, and by keeping its cross section substantially equal to the cross section of the magnetic poles. By making the length of the return circuit as short as possible, the magnetizing 50 coils are brought close together and the arc chamber between the coils is extremely shallow. The arc chamber thus becomes so shallow that it is not possible to provide a door or hand hole through the casing into 55 the chamber, which is necessary for the purpose of inspection and cleaning of the arc chamber and its contents. In the present construction, however, I overcome the necessity of a door or hand hole, by forming the 60 generator in two sections, preferably superposed, hinged together, so that by raising the upper section, ready access may be had to the arc chamber. The upper portion of the arc chamber is formed in the upper section 65 and the lower portion is formed in the lower section, so that when the upper section is closed, a closed arc chamber is provided and when it is raised, the entire arc chamber is exposed.

The generator is formed in two sections, the lower section 2 and the upper section 3, which is preferably hinged at 4 to the lower section, so that it may be readily moved. The sections are preferably cylindrical in 70 shape and preferably comprise steel shells 5—6 which form the return magnetic circuit. The upper shell 5 is closed at the top with a steel counterpoise 7 to which is secured the upper magnet pole 8. Surrounding the 75 magnet pole 8 is a magnet coil 9 which is held in place by the cover plate 12, secured to the counterpoise 7 by the bolts 13. Secured to and disposed below the cover plate 12 is an upper cooling plate 14, having depressions therein, which with the surface of cover plate form a channel or passage 15 through which water is circulated for the purpose of keeping the arc chamber cool and preventing a large flow of heat to the magnetizing winding 9. The upper cooling plate 14 forms the upper wall of the arc chamber.

When the upper section is closed, it rests directly on the lower section, forming a 105 close joint therewith and providing a return magnetic path of low reluctance. The lower shell 6 is closed at the bottom by the

steel counterpoise 15 to which the lower magnet pole 16 is secured. This lower pole is preferably longer than the upper pole and is surrounded by a magnet winding formed in three coils 17-18-19, all of the coils in the generator being preferably connected in series. Bearing against the upper coil 17 is a lower closing plate 21 and engaging the lower closing plate is a lower cooling plate 22 which is formed to provide a cooling water channel 23 having the same purpose as the channel 15. Each cooling water channel 15 and 23 is provided with inlet and outlet fixtures, so that water may be circulated through the channels. The lower cooling plate 22 forms the lower wall of the arc chamber.

Secured to the lower section is a carbon electrode holder 24 in which the carbon electrode or cathode 25 is disposed and through which it extends into the arc chamber. The lower section is also provided with an anode holder 26, suitably insulated from the section and supporting the anode 27. In the present construction, the electrodes are disposed at right angles to each other and their inner ends lie between the magnet poles, so that the arc is subjected to a strong transverse magnetic field. The cooling plates are provided with depressions which form channels in the arc chamber in which the electrodes are disposed.

The hydrogen atmosphere is produced in the arc chamber by introducing liquid hydrocarbon into the chamber. Arranged on the upper section is a hydrocarbon liquid feed cup 28 from which the liquid drips into a duct 29 extending through the upper magnet pole. The chamber is also provided with an exhaust pipe 31, to permit the discharge of the exhausted atmosphere.

By hinging the whole upper section of the generator, I not only am able to obtain a very highly efficient magnetic circuit, but also provide for extreme and ready accessibility to the arc chamber. The electrodes are disposed in the lower section of the generator, so that their position is fixed and they may be observed in their operative position by tilting back the upper section.

I claim:

1. A radio oscillation generator, comprising a shell of magnetic material, plates of magnetic material closing the ends of the shell, magnet poles in contact with said plates, magnet windings surrounding said poles and electrodes between which an arc may be formed disposed in the magnetic field between said poles.
2. A radio oscillation generator comprising a steel shell, steel plates closing the ends of said shell, magnet poles in contact with said plates and disposed within said shell with the inner ends of the poles adjacent each other, magnet windings within the

shell and surrounding the poles and electrodes having their ends disposed between the inner ends of the poles.

3. A radio oscillation generator comprising a cylindrical steel shell, steel plates closing the ends of the cylindrical shell, alined magnet poles arranged within the shell and in engagement with said plates, magnet windings surrounding said poles, an arc chamber in the shell into which the poles project and electrodes in said chamber having their inner ends disposed between said poles.

4. A radio oscillation generator comprising a cylindrical steel shell, steel plates closing the ends of the shell, alined magnet poles in the shell engaging said plates, the inner ends of the poles being spaced apart, magnet windings surrounding said poles, an arc chamber in the shell into which the inner ends of the poles extend, cooling medium circulating passages disposed between the arc chamber and the windings and electrodes in said chamber having their inner ends disposed between the poles.

5. A radio oscillation generator comprising a shell of magnetic material, magnet poles secured to opposite sides of said shell and disposed within the shell, magnet windings on said poles, an arc chamber formed in said shell between said windings, cooling plates forming the walls of said chamber provided with passages through which water may be circulated, means for producing a hydrogen atmosphere in said chamber and electrodes in said chamber between which an arc may be formed, said electrodes being disposed so that the arc will be formed between the magnet poles.

6. A radio oscillation generator comprising a shell of magnetic material formed in two separable sections, a magnet pole in each section in magnetic contact with the section, a magnet winding on each pole and an arc chamber between said sections.

7. A radio oscillation generator, comprising a shell of magnetic material formed in two separable sections, a magnet pole and a magnet winding in each section, the magnet pole being magnetically connected to the section, an arc chamber wall disposed in one section and an arc chamber wall disposed in the other section.

8. A radio oscillation generator comprising a shell of magnetic material formed in two separable superposed sections, the shell forming a return magnetic circuit, a magnet pole arranged in each section, the two poles being alined and having their inner ends spaced apart, a magnet winding surrounding each pole and plates disposed adjacent the windings and forming an arc chamber which may be opened by raising the upper section.

9. A radio oscillation generator comprising

ing a steel shell formed in two separable superposed contacting sections, an arc chamber in said shell at the juncture of said sections, and means within the sections for producing a magnetic flux across said chamber.

10. A radio oscillation generator comprising a lower steel section, an upper steel section hinged thereto, the two sections forming a closed shell, a magnet pole in each section magnetically connected thereto, a magnet winding surrounding each pole, and electrodes mounted in the lower section and having their ends disposed between said magnet poles.

11. A radio oscillation generator comprising a lower steel section, an upper steel section hinged thereto and forming with the

lower section a closed shell, a magnet pole in each section magnetically connected thereto, said poles being in alinement and having their inner ends spaced apart, a magnet winding surrounding each pole, an arc chamber in said shell, having its upper wall secured to the upper section and its lower wall secured to the lower section, and electrodes mounted on the lower section and having their ends disposed in said chamber between the magnet poles.

In testimony whereof, I have hereunto set my hand at Palo Alto, California, this 29th day of December, 1919.

RALPH R. BEAL.

In presence of—

MARTHA A. LUNSFORD.
